COIN TILL

Bruce K. Slonberger, Dayton, Ohio, assignor to
The National Cash Register Company, Dayton,
Ohio, a corporation of Maryland

Application July 11, 1950, Serial No. 173,144

13 Claims. (Cl. 206—0.84)

1

This invention relates to a coin storage and coin counting device, arranged in a coin till.

The object of the invention is to provide a coin till with storage compartments for storing and counting coins.

A specific object of the invention is to provide a coin till, of the kind usually provided in cash drawers, with a plurality of storage compartments beneath the bottoms of the conventional coin trays, so that excess change can be stored and counted.

Another specific object of the invention is to provide storage and counting compartments in coin tills to provide a convenient method of storing change for the next day's business.

With these and incidental objects in view, the invention includes certain novel features of construction and combinations of parts, a preferred form of which is hereinafter described with reference to the drawing which accompanies and forms a part of this specification.

In said drawing,

Fig. 1 is a top plan view of a fragmentary portion of a coin till.

Fig. 2 is a cross sectional view of one compartment of the coin till, taken on line 2—2 of Fig. 1, and looking in the direction of the arrows.

Fig. 3 is a cross sectional view taken on line 3—3 of Fig. 2, looking in the direction of the arrows.

Fig. 4 is a cross sectional view similar to Fig. 2, with the coin till bottom removed, and shows one means for removing coins from the storage compartment.

Fig. 5 is a cross sectional view through the "dimes" storage compartment.

Fig. 6 is a detail perspective view of a device for removing a stack of coins from a storage compartment.

General description

As is well known, merchants operating retail stores use coin tills from which change is made. During the course of a day's business, the number of coins of each denomination varies from time to time. This results in the accumulation of either too many coins of a certain denomination, or too few. The present invention provides a novel coin till for making a normal supply readily available for making change and also with convenient storage for excess coins when needed, and also a convenient storage for coins at the end of a day's business, so that the desired number of coins are available to start the day's business. The storage compartments are nor-

2

mally hidden from view, being located beneath the bottoms of the coin till trays.

The storage compartments are constructed with dividing walls spaced apart to receive coins resting on their edges in rows, and the number of spaces provided in each row equals the number of coins usually packed in one roll by banks. For example, in the "nickel" compartment, twenty spaces are provided. Therefore, when 10 a row of spaces is filled, the clerk or proprietor can quickly total the number of coins stored by simply glancing at the rows of coins.

The coins are suspended in the rows on rods or washers on the rods, and the under sides of 15 the compartments are open, so that the coins are exposed.

To transfer coins from a storage row into the till, the following steps are taken. First, the removable bottom of a till is removed, thus exposing the coins to view. Next, the clerk reaches under the compartment and forces the desired number of coins upwardly, where they drop on the top edges of the partitions forming the spaces for coin storage. Next, the removable till bottom is slipped in under the coins resting on the partitions, starting from the front of the till, in a scooping-like action, until the rear edge of the bottom passes below the rear wall of the till compartment, there being sufficient space provided for this result.

It has been found that in the average retail store one roll of coins is sufficient, such as, for example, twenty nickels, for the start of a day's business. To provide for maintaining this number of nickels in the storage compartment at the 35 end of a day's business, a means is provided to lock one row of coins in each storage compartment. Thus, at the end of a day, if the till is upended to remove all excess coins, the coins locked in this one row will be retained in the compartment.

A device is also provided to remove a row of coins preparatory to wrapping them for deposit in a bank or otherwise placing them in safe 45 keeping; for example, in a safe or vault. This device consists of a partial tube made of resilient material, and the inside diameter is such that the device can be forced over a row of coins in the storage compartment to frictionally hold them therein. Upon the device's being lifted, the row of coins can be raised herewith and wrapped in the usual manner after the coins are released from the device.

Detailed description

55 Each till is provided with side walls 10, pro-

vided with a series of cut-out portions on their lower sides, to form legs 11 (Fig. 4). The number of legs provided will be governed by the depth of the coin till and the number of rows of coins to be stored. As illustrated herein, the tills are arranged for storing four rows of coins. A plurality of partitions 12 (nineteen are illustrated in Fig. 3) are provided, and the lower edges of these partitions are formed to coincide with the lower edge of the side walls, thus forming a series of legs 13. The legs 11 and 13 are pierced to receive rods 14, and washers 15 are positioned on the rods 14 to space the partitions. The size and thickness of the washers are governed by the coin to be stored in the particular compartment. For example, if nickels are to be stored, the thickness of the washers will be greater than for dimes, but their diameter will be smaller. Fig. 4 illustrates a compartment for storing nickels 16, and Fig. 5 illustrates a compartment for storing dimes 17. By providing washers 15 of different diameters, coins of different diameters can be suspended in the rows, and their diameters must be such as to permit the coins to drop into the spaces between the partitions, but not through.

The partitions 12 and the side walls 10 are also pierced to receive a rod 20, on which washers 21 are spaced, which washers are of the same thickness as the selected washers 15 to side-space the upper terminal of the partitions 12. The diameters of the washers 21 are such as to conform to the configuration of the upper terminal of said partitions to provide a smooth round edge.

The side walls 10 are also pierced at the upper rear ends to receive a rod 22. After the rods 14, 20, and 22 are properly assembled, their ends are riveted, or otherwise upset, to assemble the side walls 10 and the partitions 12 into a solid unit. An additional rod 23 spans the compartment and is riveted at each end against the side walls 10 to provide a finger piece for removing a till from the cash drawer when desired.

The rear end of the till is enclosed by a wall 25 curved upwardly at its lower end to form an anchor 26 frictionally held against the lower ends of the rear legs 11 and 13. The upper end of the wall is formed to fit around the rod 22 and is provided with a downwardly-extending portion 27. The lower end of the portion 27 extends to a position just above a removable bottom 28 for the change-making till, and the portion 27 is resiliently biased inwardly for a purpose described later.

The till bottom 28 extends between the side walls 10 and is rounded at its forward end to provide for easy removal of coins therefrom. The upper extension of the curved end of the bottom 28 is curved to fit the upper extension of the partitions 12 and the washers 21 on the rod 20, and thence is formed downwardly to provide an apron 29. The bottom 28 is removable from the till by first lifting the forward end off of the washers 21 and then sliding it forwardly and upwardly. In this way, access can be had to the coins stored in the storage compartments.

When it is desired to store coins in the storage compartments, the bottom 28 is removed in the manner described, which permits the coins to rest on the upper edges of the partitions 12. The coins are then inserted between the partitions, where they come to rest on the washers 15. To prevent the coins from falling out of the front end of the till, rods 30 and 31 are provided, and the rod 30 is provided with a washer 32 to guide the coins into the front compartment.

The rear compartment is selected for storing coins overnight. At the end of a day's business, the till is turned over to remove all the loose coins therefrom. Since it is desired not to remove the coins from the rear compartment, means is provided to prevent them from falling out at such times. To lock the coins in the rear compartment, a movable rod 35 is mounted in slots 36 in the partitions 12. The rod is provided with washers 37, which fit frictionally between the partitions, so that pressure is required to move the rod. Also, as before mentioned, the portion 27 of the rear wall 25 is biased inwardly, and this projects its lower end into the path of movement of the coin as it is inserted, as illustrated by chain lines in Fig. 4. The pressure exerted on the coin by the biased portion 27 is sufficient to overcome the friction holding the rod 35 and the washers 37 in position, and therefore the coin causes the rod 35 to move forwardly until the coin passes the washers 37 and drops into position. At this time, the portion 27, being biased, springs back to normal position into the path of movement of the coin, thus locking the coins in position against accidental removal. To remove the coins from this compartment, the clerk pushes up on the coin from the under side of the till, whereupon the coin, coming into contact with the biased portion 27, flexes it rearwardly to release the coin.

Each unit, comprising two side walls 10 and partitions 12, is a separate entity. The desired number of units are positioned in a cash drawer, or other receptacle, between two walls 41 formed therein. If desired, these separate units can be removed from the cash drawer at the end of a day's business and stored in a safe or vault. The cashier can then credit the clerk with coins turned in and thereafter store the change necessary for the next day's business in the rear compartment of the unit.

As before mentioned, the storage compartments are provided with partitions to store twenty nickels in a row. To facilitate removal of the coins all at one time for wrapping, a device 40 is provided, of such inside radius as to fit the edges of the coins frictionally. The device is slightly greater than a semi-circle. To remove the coins from a row, the device 40 is placed over a row, as illustrated in Fig. 4, and the coins are forced upwardly into the device, where they are held frictionally, and they can therefore be removed as a group. If nickels are removed and a row is full, the clerk will know that one dollar in nickels is being removed. They can be transferred from the device 40 directly to a paper wrapping tube. As it is customary to wrap forty nickels in a tube, the clerk must remove two rows of nickels for this purpose.

While the form of the invention shown and described herein is admirably adapted to fulfill the objects primarily stated, it is to be understood that it is not intended to confine the invention to the one form or embodiment disclosed herein, for it is susceptible of embodiment in various other forms.

What is claimed is:

1. In a device of the class described, the combination of a coin till, a removable bottom in the coin till, a plurality of spaced partitions to normally support the bottom, said partitions spaced apart in equidistant relationship to each other to provide spaces for coins, and a plurality of supporting devices arranged between the partitions, said supporting devices comprising supports for coins standing on edge.

2. In a device of the class described, the combination of a coin till, a removable bottom in the coin till, a plurality of spaced partitions to normally support the bottom, said partitions spaced apart in equidistant relationship to each other to provide spaces for coins standing on their edges and a plurality of supporting devices arranged between the partitions, said supporting devices located below the said bottom to support coins on their edges, below the bottom.

3. In a device of the class described, the combination of a coin till, a removable bottom in the coin till, a plurality of spaced partitions to normally support the bottom, said partitions spaced apart in relationship to each other a distance equal to the thickness of a coin to provide spaces for coins standing on their edges and a plurality of supporting devices arranged between the partitions, said supporting devices comprising disks slightly thicker than the thickness of a coin and located a sufficient distance below the said bottom to support coins on their edges below the said bottom.

4. In a device of the class described, the combination of a coin till, a removable bottom in the coin till for receiving coins lying flat, a plurality of partitions below the removable bottom and spread apart to receive coins on their edges, fingers formed on the under side of the partitions, finger openings formed between the fingers, and supporting devices on the fingers located a distance from the removable bottom to support coins on their edges, said finger openings providing means for permitting expulsion of coins from the supports and from between the partitions.

5. In a device of the class described, the combination of a plurality of partitions equidistantly spaced apart in parallel arrangement, said partitions being uniform in contour, a framework, devices supported in the framework and projecting through said partitions to support the latter, and a coin tray removably supported on the top edges of the partitions.

6. In a device of the class described, the combination of a plurality of partitions equidistantly spaced apart in parallel arrangement, said partitions being uniform in contour, a framework, devices supported in the framework and projecting through said partitions to support the latter, a coin tray removably supported on the top edges of the partitions, another device supported by the framework, and means formed on the tray and frictionally engageable with said another device to maintain the tray in position.

7. In a device of the class described, the combination of a plurality of partitions equidistantly spaced apart to receive coins on edge, all of said partitions being uniform in contour and arranged in parallel order to provide slots, devices to divide the slots in uniform rows and to support the coins in the slots, a framework to support the devices, and a removable coin tray supported on the upper edges of the partitions to close the slots and provide a coin tray for receiving coins.

8. In a device of the class described, the combination of a plurality of partitions equidistantly spaced apart to receive coins on edge, all of said partitions being uniform in contour, having horizontal upper edges, and arranged in parallel order to provide slots, devices to divide the slots in uniform rows and to support the coins in the slots, a framework to support the devices, and a removable coin tray supported on the said horizontal edges of the partitions to close the slots and provide a coin tray for receiving coins.

9. In a device of the class described, the combination of a plurality of partitions equidistantly spaced apart to receive coins on edge, a framework to support the partitions, supporting elements in the spaces between the partitions arranged to divide the coins in the said spaces into rows, and means to releasably lock at least one row of coins in said spaces.

10. In a device of the class described, the combination of a plurality of partitions equidistantly spaced apart to receive coins on edge, a framework to support the partitions, supporting elements in the spaces between the partitions arranged to divide the coins in the said spaces into rows, and a movable means supported by said partitions and movable into a position above at least one row of said coins to releasably maintain the coins in said spaces.

11. In a device of the class described, the combination of a plurality of partitions equidistantly spaced apart to receive coins on edge, a framework to support the partitions, supporting elements in the spaces between the partitions arranged to divide the coins in the said spaces into rows, a rod movably mounted in said partitions and disposed to span all the partitions, and a washer mounted on the rod in each of said spaces, said rod and washers movable into position over one row of coins to maintain the coins in said spaces.

12. In a device of the class described, the combination of a plurality of partitions equidistantly spaced apart to receive coins on edge, a framework to support the partitions, supporting elements in the spaces between the partitions arranged to divide the coins in the said spaces into rows, a rod movably mounted in said partitions and disposed to span all the partitions, and a washer mounted on the rod in each of said spaces, said rod and washers movable into position over one row of coins to maintain the coins in said spaces, said washers being of a thickness to cause them to be frictionally held in any moved position.

13. In a device of the class described, the combination of a plurality of partitions equidistantly spaced apart to receive coins on edge; a framework to support the partitions; supporting elements in the spaces between the partitions arranged to divide the coins in the said spaces into rows; a rod movably mounted in said partitions and disposed to span all the partitions; a washer mounted on the rod in each of said spaces, said rod and washers movable into position over one row of coins to maintain the coins in said spaces, said washers being of a thickness to cause them to be frictionally held in any moved position; and a resilient plate located above the top edges of the partitions and biased to restrict the space through which coins are inserted into the spaces for said one row of coins, said resilient means obstructing removal of the coins after the coins have passed the end thereof.
